UNITED STATES PATENT OFFICE

GEORGE PONAROUSE, OF SAN FRANCISCO, CALIFORNIA

HAIR CURLER

Application filed September 13, 1929. Serial No. 392,339.

This invention relates to improvements in hair curlers and has particular reference to the type of hair curler utilized by women to produce a wavy effect when the curlers are removed and the hair is combed.

The principal object of the invention is to provide a device of the character described which is simple in construction, compact and one which will readily form the desired curl. 10 An additional object is to provide a heating element in conjunction with the curler whereby the curl can be formed in a minimum amount of time.

A further object is to provide a curler 15 which is simple, neat in appearance and economical to manufacture.

Other objects and advantages will be apparent during the course of the following description.

20 In the accompanying drawings forming a part of this specification and in which like numerals are employed to designate like parts throughout the same,

Figure 1 is a perspective view of the curler 25 formed in accordance with my invention,

Figure 2 is an edge elevation of the same,

Figure 3 is a side elevation of the curler,

Figure 4 is a perspective view of the device 30 showing a curler formed thereon,

Figure 5 is a cross-section through the curler disclosing the interior construction thereof,

Figure 6 is a horizontal section on the line 35 6-6 of Figure 3, and

Figure 7 is a perspective view of the heating element inserted in the curler.

In the accompanying drawings wherein for the purpose of illustration is shown a preferred embodiment of my invention, the numeral 8 designates a cylindrical tubular casing that is split at one end as shown at 9 to provide two laterally extending ends 10 and 11 which have hingedly secured thereto a wire loop element 12.

The opposite end of the curler is bifurcated as at 13 with slots 14 provided near the bifurcated end for frictionally holding in contact with the curler 8, the wire loop 12. In the 50 bifurcated end of the curler there is secured

a cord 15, the purpose of which will be later described.

As disclosed to advantage in Figures 5 and 7, the numeral 16 designates a heating element that has secured thereto a spring 55 loop 17 that serves as a hand hold when it is desired to manipulate the curler and functions to receive therein the cord 15 to prevent accidental displacement of the heating element from the curler. 60

It will be noted that an asbestos filler, as shown to advantage in Figure 5, is utilized within the casing 8 so that danger of burning the cord will be eliminated.

In practice the hair adjacent the free ends 65 thereof is placed over the casing 8. The loop element 12 is then moved from its position shown in Figure 1 to that disclosed in full lines in Figure 2 and the ends of the hair tightly gripped by the casing and loop. The 70 heating element 16 is then inserted in the end 9 and when thus positioned, finger holds are provided by the wire loop 17 and end 75 of the member 12. A rotation of the curler toward the head will then cause the curler, as indicated by the numeral 20 and disclosed to advantage in Figure 4, to be formed on the device.

For the purpose of holding the curl in a fixed position for the predetermined length 80 of time, the cord 15 is drawn over the curl and received in the wire 17.

Figure 4 discloses one manner in which the end of the cord can be secured to the member 17. 85

It is obvious that any method may be employed that will serve to prevent displacement of the member 17 from the casing 8.

From practise, I have ascertained that with this simple and economically constructed device a curling of the hair can be accomplished in a minimum amount of time. 90

It is to be understood that the form of my invention herewith shown and described is to be taken as a preferred example of the 95 same and that various changes relative to the shape, size, material and arrangement of parts may be resorted to without departing from the spirit of the invention, or the scope of the subjoined claims. 100

Having thus described my invention, I claim:—

1. A hair curler comprising a tubular casing, split at one end and bifurcated at its opposite end, an elongated frame hingedly connected to the split end and receivable over the bifurcated end of said casing for initially locking the strands of hair to said casing, and a curl holding cord fixedly secured to the bifurcated end of said curl and detachably secured to the opposite end thereof.
2. A hair curler comprising a tubular member, an elongated wire frame connected to one end of said member and adapted to be received over the opposite end of said member, a curl retaining element carried by said tubular member and a heating element positioned in said member, and including a wire loop that co-operates with the free end of the wire frame to provide a finger hold in the forming of the curl.
3. A hair curler comprising a tubular member, an elongated wire frame hingedly connected to one end of said member and adapted to be received over the opposite end of said member, means carried by said member for fixedly holding a portion of the elongated frame thereon, a heating element positioned in said member and including a wire loop, a curl retaining element carried by said member and comprising a cord positioned in one end of said tubular member, and detachably secured to the wire loop of said heating element.
4. A hair curler comprising a tubular casing, split at one end and bifurcated at its opposite end, an elongated frame hingedly connected to the split end and receivable over the bifurcated end of said casing for initially locking the strands of hair to said casing, and a curl holding cord fixedly secured to the bifurcated end of said curl and detachably secured to the opposite end thereof, and a heating element positioned in said member, said heating element including a wire loop that co-operates with the free end of the wire frame to provide a finger hold in the forming of the curl on said casing.
5. A hair curler comprising a casing split at one extremity to provide laterally extending ends, an elongated loop frame hingedly connected to laterally extending ends and receivable over the opposite end of the casing for initially locking the strand of hair to said casing, and a curl holding cord fixedly secured in one end of said casing and detachably secured to the opposite end thereof.

In testimony whereof I affix my signature.
GEORGE PONAROUSE.
